UNITED STATES PATENT OFFICE.

EDGAR M. BOUTON, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTROMAGNET.

Application filed January 16, 1920. Serial No. 351,847.

To all whom it may concern:

Be it known that I, EDGAR M. BOUTON, a citizen of the United States, and a resident of Wilkinsburg, in the county of Allegheny and State of Pennsylvania, have invented a new and useful Improvement in Electromagnets, of which the following is a specification.

My invention relates to electromagnets and it is particularly applicable to electromagnets that are employed in the operation of brakes and which are exposed to moisture.

The object of my invention is to provide an effective, durable, inexpensive and conveniently constructed waterproof electromagnet for operating a braking device.

Heretofore, electromagnets for operating brake mechanisms that are subjected to moisture have been enclosed in moisture-proof casings. Since it has been the practice to locate the movable armature of such electromagnet within the case, it is necessary to encircle the connecting rod, which operatively connects the armature and the brake mechanism, by a stuffing box.

According to my present invention, I provide a simple, readily constructed waterproof magnet which has no movable parts enclosed within the casing and, therefore, no stuffing box is required. The magnet armature is entirely external to the casing and is attached to the brake mechanism which it actuates.

My invention may best be understood by reference to the accompanying drawings, in which Fig. 1 is an end view, partially in elevation and partially in section, of an electromagnetic device embodying my invention, and Fig. 2 is a side view, partially in section, of the device shown in Fig. 1.

Referring to Figs. 1 and 2, the apparatus here shown comprises a magnetizable metallic casing 1, a core member 2 rigidly mounted therein and an energizing coil 3 surrounding the core member. The casing 1 is provided with a non-magnetic cover 4, preferably of bronze. An armature member 5, which may be operatively connected to a

brake mechanism (not shown), is adjacent 50 to the cover 4. The brake armature 5 is pivotally mounted on an arm 6 of the brake base 7.

The casing 1 is rigidly mounted on a magnetizable portion of the brake base 7 by bolts 55 8. The core member 2 is secured to the casing 1 by screws 9. From one side of the casing 1 projects a cylindrical portion 10 through which extend the terminals 11 of the magnet coil 3. In addition to their insulating covering, the coil 3 and the terminals 11 are insulated from the casing 1 by waterproof cement 12 which fills the space between them and the casing and which conducts the heat from them to the casing. 65

The portion 10 is closed by a steel cap 13 which has two openings 14 for the terminals 11 and their watertight insulating bushings 15. The cap 13 is attached to the portion 10 by tap bolts 16. A waterproof 70 connection of the cap 13 to the rim portion 10 is afforded by a rubber gasket 17, and a steel washer 18 attached to the inner side of the cap 13 by screws 19. The bronze cover 4 is secured to the casing 1 by means of a clamping ring 20 and screws 21. A rubber gasket 22 is positioned between the casing and the cover. Between the cover 4 and the waterproof cement 12, is placed a layer 75 of felt 23. A steel disc 24 and a bronze washer 25 are mounted upon the cover 4 and they are secured to the core member 2 by means of a tap bolt 26. A lock washer 27 prevents the tap bolt 26 from becoming disengaged. 80

Two opposite sides of the casing 1 have integral lugs 28 which project outwardly so their flat surfaces lie in the same plane as the outer face of the disc 24. These surfaces attract the corresponding surfaces of the armature member 5, when the coil 3 is energized. The lugs 28 and the disc 24 constitute the pole pieces of the electromagnet, which, as will be noted, are external to the casing. 85

The principal path of the magnetic flux is through the core member 2 and the steel disc 24 to the armature member 5 and thence,

through the armature member, the lugs 28 and casing 1, to the core member 2. A secondary path is through the core member 2, the casing 1, the brake base 7, and the 5 armature member 5 to the core member 2.

A mechanical means for operating the brake armature 5 comprises an arcuate member 29 that is secured to the sides of the casing 1 by tap bolts 30 and is so arranged that 10 the armature member 5 is between it and the cover 4 and is at right angles to it. In the center of the member 29 is a threaded opening 31 for a threaded member 32, which is operated by a hand-nut 33. A taper pin 15 34 is used to maintain the engagement of the threaded member 32 with the hand-nut 33. All crevices of the structure are filled 20 with waterproof cement and the casing and external parts of the electromagnetic device are coated with shellac or other protecting composition.

The electromagnet embodying my invention is operated by energizing the coil 3 to magnetize the core member 2, the casing 1, 25 the brake base 7, the disc 24, and the lugs 28, thereby causing the contact faces of the armature member 5 to engage the bronze washer 25, thus substantially completing the magnetic circuit. When the coil 3 is de- 30 energized, the armature member 5 is released and returned to the position shown in the accompanying drawing by the usual springs of the brake mechanism (not shown).

35 The brake arm may be operated without the use of electrical energy by turning the hand-nut 33 to rotate the threaded member 32 and thus actuate the armature 5. This arrangement provides means for manually 40 operating the brake mechanism in case of emergency, such, for example, as that caused by failure of voltage of the source of energy.

45 My improved device having no moving parts within the casing, is made dust and waterproof, and, being thus protected, the parts will have great durability. The moving parts of the brake mechanism, being un- 50 enclosed, may be conveniently inspected and repaired. The hand-brake mechanism is compact and, being attached to the casing, permits of convenient operation when elec- 55 trical energy is not available.

I have shown a simple and preferred form 60 of my invention, the details of which may be subject to slight modifications. I desire, therefore, that only such limitations shall be imposed as are indicated in the appended claims.

I claim as my invention:—

65 1. In an electromagnetic braking device, the combination with an electromagnet, a case for enclosing the said electromagnet, and an external armature member for actuating a brake mechanism, said member being

actuated by the said electromagnet, of 65 mechanical means mounted upon the said case for actuating the said armature member.

2. In an electromagnetic braking device, 70 the combination with an electromagnet, a case for partially enclosing the said electromagnet, and an external armature, of mechanical means mounted upon the said case for actuating the said armature member.

3. In an electromagnetic braking device, 75 the combination with an electromagnet, a waterproof case for enclosing the said electromagnet, and an external armature member actuated by the said electromagnet, of 80 mechanical means mounted upon the said case for actuating the said armature member.

4. In an electromagnetic braking device, 85 the combination with an electromagnet, a water-proof case for substantially enclosing 90 the said electromagnet, and an external armature member, of mechanical means comprising a rotatable member mounted upon the said case for actuating the said armature member.

5. In an electromagnetic braking device, 95 the combination with an electromagnet, a casing for the said electromagnet, and an external armature member, of means comprising a hand-operated device attached to the 100 said casing for operating the said armature member.

6. In an electromagnetic braking device, 105 the combination with a core member, of a coil surrounding the said member, a casing enclosing and positioning the said member and the said coil, a cement filler placed between the said coil and the said casing to 110 protect the said member and the said coil from moisture, a magnetizable disc mounted upon the said casing, and connected with said core member, an armature member external to 115 said device, and mechanical means for operating the said armature.

7. In an electromagnetic braking device, 120 the combination with a magnetizable casing having lugs, of a core member mounted in 115 said casing, an energizing coil surrounding the said member and having terminals outside the casing, a cover for the said casing, a waterproof material positioned between the said coil and the said casing, a disc mounted upon the said cover and magnetically connected with the said core, and an external armature member actuated by a magnetic circuit comprising the said disc and the said lugs.

8. In an electromagnetic braking device, 125 the combination with a magnetizable core member, an energizing coil, a magnetizable casing enclosing the said member and the said coil, and an external armature member which is actuated by the said member

and the said casing, of mechanical means attached to the said casing for operating the said armature member.

9. In an electromagnetic braking device, 5 the combination with a magnetizable core member, an energizing coil, a magnetizable casing for enclosing and for positioning the said member and the said coil, and a magnetizable brake base on which is mounted 10 the said casing, of an armature member

pivottally mounted on the said base and constituting a portion of two parallel magnetic circuits, one of which extends through the said core member and the said casing, and the other of which extends through the said 15 core member and the said brake base.

In testimony whereof, I have hereunto subscribed my name this 17th day of December, 1919.

EDGAR M. BOUTON.
